METHOD FOR PRODUCING CUTTER BLADES
FOR SLICING MACHINES

John Hansen, Bettendorf, Iowa

Application July 1, 1933, Serial No. 678,631

9 Claims. (Cl. 51—278)

This invention relates to a method of producing cutter blades, and particularly cutter blades for use in slicing machines. The blade set forth herein is of special service in bread-slicing machines.

One of the objects of the present invention is to provide a new and improved method of producing a cutter blade having a cutting edge in the form of a series of indentations.

10 Another object is to provide a method of beveling one or both edges of the indentations of such a blade whereby to form the blade with a keen cutting edge. The more satisfactory way is that of beveling both edges, with a cutting edge in the center.

15 Another object is to provide a method of beveling the edges of the indentations of a cutting blade having an indented cutting edge, in such manner that the beveled portions of adjacent indentations substantially terminate and intersect each other in a series of points in alignment with

20 each other on a center line of the blade.

Another object is to provide a method whereby such blades can be economically and expeditiously produced with great accuracy by the use of simple means.

25 A further object is to provide a method of producing such blades wherein accuracy in the production thereof can be maintained, which accuracy is not greatly dependent upon the contour of the face of the abrasive means employed in forming the cutting edges of the blade.

30 A still further object is to provide a method of forming cutting blades in which a thin resilient blade is presented in a curved shape to an abrasive means, in such manner that the abrasive means removes a portion of the metal from the curved surface at the cutting edge to provide an indentation at such edge or to bevel the edge of the indentation when such indentation is performed in the blade. The bending of the blade is only temporary, such blade being restored at the end of the operation to its original form of its own resiliency.

35 Another purpose of the invention is to provide a method whereby the cutting edges of the blade can be readily and expeditiously renewed upon becoming dull, whereby the life of such blades can be greatly prolonged, and their sphere of usefulness enlarged.

40 With the above and other objects in view, which will be apparent from the following detailed description, the present invention consists in certain novel features which will be readily under-

stood by those skilled in the art to which the invention appertains.

In the drawing, which illustrates suitable embodiments of the invention:

Figure 1 is a side elevation of a strip of thin metal, preferably tempered steel or other metal possessing a high degree of flexibility and resiliency blanked out to blade-like form; 5

Fig. 2 is a side elevation of the blank showing one edge thereof further blanked to provide an indented contour at the cutting edge; 10

Fig. 3 is a further side elevation showing the shape and contour of the cutting edge of the completed blade;

Fig. 4 is an enlarged plan view of the blade 15 looking toward the cutting edge, and showing the manner in which adjacent beveled indentations of the cutting edge sharply intersect each other;

Fig. 5 is an enlarged transverse section taken 20 approximately on the line 5—5 of Fig. 3;

Fig. 6 is an enlarged transverse section taken approximately on the line 6—6 of Fig. 3;

Fig. 7 is a diagrammatic plan view showing an abrasive wheel and the blank blade of Fig. 2 25 flexed and positioned adjacent thereto in grinding position;

Fig. 8 is a side elevation of the apparatus illustrated in Fig. 7, showing the angular relationship of the flexed cutter blade and abrasive surface; 30

Fig. 9 is a modified diagrammatic view similar to Fig. 7, but showing the blank cutter blade flexed only in the region where the grinding operation is to be performed;

Fig. 10 is a further modified diagrammatic view 35 showing the flexed cutter blade in a position to be presented to the flat lateral face of a grinding wheel rather than to the circumferential face; and

Fig. 11 is a further modified diagrammatic view 40 showing the flexed blade blank positioned so that its surface is inclined in respect to the plane of the abrasive wheel.

Referring to the accompanying drawing, in which like numerals refer to like parts throughout the several views, the cutter blade 1 to be formed in accordance with my invention is in the form of a suitable resilient metal strip, and the cutting edge thereof is provided with a series of indentations 2, preferably curved, which provide 45 for the spaced points 3, as shown in Fig. 2. In order to provide keen cutting edges, the blade 1 is beveled at least at one side (here, however, the blade is shown as beveled at both sides), and it will be noted that the curved facet or bevel 4 for 50

55

each indentation 2 sharply intersects the corresponding bevel 4 of the next adjacent indentation in a relatively sharp edge or ridge 5 which likewise is beveled from the side of the blade to the point 3.

It has been found that by so forming the cutting edge with distinct and sharply pronounced edges or ridges 5 between adjacent bevels of the indentations 2, materially advantageous results are obtained with cutter blades of this character, and particularly so when such blades are used in connection with the slicing of soft articles, such as bread. In the operating position of the blade these points are in alignment with each other, and upon the blade being given the usual reciprocating movement the points move back and forth along a straight line of incision.

In producing the cutter blade in accordance with the method of my invention, I employ an abrasive means, such as the rotatable grinding wheel 6 shown in the drawing, it being understood, however, that other forms of abrasive means, such as disc grinders, reciprocable abrasive means or any other tools of the kind suitable for the purpose may be employed, and that these come within the scope of my invention.

The blade blank may be directly acted upon to completely form the indentation 2 during the grinding operation, but it may, if desired, be first provided with the indentations 2 through the medium of a separate blanking operation in order to obviate the necessity of removing the surplus metal by abrasion, and then employ the grinding operation to provide the curved facets or beveled surfaces 4 at the edges of the indentations.

In the preferred form of my method the blade 1 which is blanked to the shape illustrated in Figs. 1 and 2 is flexed, as shown in Fig. 7, to a curved shape in which shape it is held during the grinding operation. This may be accomplished, of course, by mounting the same on a suitable jig or mandrel (not shown). In the case shown the jig would be of circular form, and the blade would be curved thereon throughout its length. The blade in its flexed form is then disposed adjacent the abrasive wheel with the flat surface of the blade at an angle to the circumferential face of the wheel, as indicated in Fig. 8, and is then moved parallel to the grinding wheel face from the position indicated at "A" in solid outline to the position indicated at "B" in dotted outline in Fig. 7. This passage of the blade across the face of the grinding wheel removes a portion of the curved surface of the blade side at the cutting edge and bevels the edge of the indentation 2. If, however, the indentation was not previously formed, such passage across the face of the abrasive means would also form the indentation 2, as well as the bevel 4, by reason of the angular position of the blade relative to the face of the grinding wheel.

After this movement of the blade across the face of the grinding wheel, the blade is given a predetermined indexing movement in the direction of its length, corresponding to the space of one indentation 2, to present another curved blade portion to the abrasive wheel, and the process is then repeated until the blade is completed at one side. Upon such completion the blade is removed from the jig, and upon being released returns at once to its original form by force of its own resiliency. When it is desired to bevel the other side of the blade, the blade is, of course, flexed in the opposite direction and the process is repeated as previously described, and in such a

manner that the indentations and bevels will occur at pre-determined locations and with the points 3 properly formed between the same.

By so grinding the bevels progressively while the blade is flexed to a curved shape, it is obvious that the bevels 4 of adjacent indentations 2 will intersect each other sharply and thus provide the pronounced ridges 5 therebetween.

Instead of moving the blade relative to the abrasive means, this blade may, however, be held stationary and the abrasive means 6 moved relative to the blade.

In some cases, such as indicated in Fig. 9, the blade may be flexed only at the region of the bevels to be ground or the indentations to be formed, and the blade progressively flexed as the successive facets 4 are to be ground or the successive indentations 2 to be formed.

As indicated in Fig. 10, the flexed blade may be angularly presented to the lateral face of the abrasive means 6 instead of to the circumferential face, or, as indicated in Fig. 11, the flexed blade may be disposed so that its surface is at an inclination to the plane of the grinding wheel 6.

In each case, however, it will be noted that the blade is flexed to a curved shape, at least at the region where the operation is to be performed, and is disposed at an angle to the face of the abrasive means, so that upon relative movements of the blade and abrasive means a body of metal is removed from the curved surface, either providing a completed bevel edged indentation 2 when a straight edge of a blade blank is acted upon, or a curved facet 4 at the edge of each indentation when the indentations are pre-formed. Since a flat portion is formed by the abrasive action through the presentation of a curved surface to a flat abrasive surface, it is obvious that these flat surfaces forming the bevels 4 will sharply intersect each other to provide the distinct and pronounced ridges 5 ending in the points 3 which materially assist the action of the cutting blade in the slicing of soft articles, such as bread. In this operation a loaf of bread is moved against the cutting edge of the blade to the depth of the indentations, and as the incision is made a movement of the blade in one direction forces one half of each arc-shaped edge, between a line indicated in Fig. 3 by the broken line 5-5 and one of the points 3, into the bread. Another movement of the bread follows, and the return action of the blade produces a similar effect with the other halves of the arcuate edges. It is therefore essential that the points be in a straight line.

If desired, the indentation or bevel could be formed by moving the flexed blade at right angles to the face of the abrasive means, that is, in a direction at right angles to the axis of the grinding wheel, instead of passing the same across a face of the abrasive means. But here the accuracy of contour would be somewhat dependent upon the face of the abrasive means being and remaining true, especially when it is desired to bevel both sides of each indentation.

By presenting the flexed blade to the abrasive means at an angle and moving the same across the face of the abrasive means, I have provided a method of producing indented cutting blades wherein accuracy in the production of such blades can be maintained without the same being greatly dependent on the contour of the face of the abrasive means.

The indentations and bevels may be formed at both edges of the cutter blade, in the manner pre-

viously described. Furthermore, the indentations along the edge of the blade may be alternately formed, that is, one indentation may be beveled at one side of the blade and the next adjacent indentation beveled at the opposite side of the blade. The bevels and indentations may be of different lengths along the edge of the blade and may also be of different depths.

When the blades have become dull through use they can be removed from the machine and resharpened in the same manner as has been pointed out herein for producing the blades in the first instance.

Aside from the specific embodiments of the invention herein described, it will be understood that numerous changes may be made without departing from the spirit and scope of the invention, and I do not desire to limit my invention to the exact procedure herein set forth, as I desire to claim the same broadly as well as specifically, as indicated in the appended claims.

What I claim is:

1. The method of making a cutting blade, which comprises bending a straight resilient blade to produce a definite curvature therein, holding one edge of said blade in its bent form and passing the same across the face of an abrasive means to remove a body of metal from the bent surface to produce a curved facet in its cutting edge, said blade upon being released being restored by force of its own resiliency to its shape before being bent.

2. The method of making a cutting blade, which comprises bending a straight resilient blade to present a definitely curved surface, holding said blade in its bent form and passing the same while so held across the face of an abrasive means in such a plane as to remove metal from the curved surface to produce a beveled indentation in its cutting edge, and shifting said blade longitudinally of itself to form a plurality of such beveled indentations, said blade upon being released being restored by force of its own resiliency to its shape before being bent.

3. A method of making a cutting blade possessing resilient qualities, which comprises providing an edge thereof with a series of indentations with alternating points in alignment with each other, bending and holding said indented blade in its bent form and applying an abrasive element to each indentation to provide a beveled facet therefor, bending said blade into oppositely bent form in properly gauged position with relation to said indentations, and repeating the operation on the opposite side thereof, forming a wedge-shaped cutting edge throughout said indentations and points.

4. A method of making a cutting blade, comprising bending and holding said blade to a curved shape with a predetermined arc, passing an abrasive means across said blade at a curved surface thereof in a plane to remove a portion of such curved surface and produce a beveled indentation in the cutting edge of said blade,

shifting said blade longitudinally of itself to repeat the formation of said beveled indentation, thereby to form a series of such indentations, reversing said blade into oppositely curved formation and repeating said process to abrade the opposite side of said blade, the shifting of the blade in the last-named process being such as to bring the blade into predetermined positions coinciding with those of the original positioning of said blade.

5. A method for sharpening a cutting blade having its edge in the form of a series of beveled indentations with alternating points in alignment with each other, which comprises flexing a resilient blade to present a substantially straight surface, applying an abrasive element to said surface with a relative lateral movement of the blade and abrasive element and repeating said application at other indentations along the length of said blade, said blade upon being released being restored by force of its own resiliency to its shape before being bent.

6. A method of making a cutting blade, comprising bending said blade to a curved shape, holding said blade in its bent shape, abrading the convex surface of said blade in a plane to remove metal from such face and produce an indentation in its cutting edge, reversing said blade into oppositely bent formation and repeating said process to abrade the opposite side of said blade.

7. A method of making a cutting blade, comprising bending said blade to a curved shape, holding said blade in its bent shape, abrading the convex surface of said blade in a plane to remove metal from such face and produce an indentation in its cutting edge, shifting said blade longitudinally of itself to form a plurality of such indentations, reversing said blade into oppositely bent formation, and repeating said process to abrade the opposite side of said blade.

8. The method of making a cutting blade, comprising bending and holding said blade to a curved shape, passing an abrasive means across said blade at a curved surface thereof in a plane to remove a portion of such curved surface and produce an indentation in the cutting edge of said blade, and shifting said blade longitudinally of itself to thereby form a plurality of such indentations.

9. The method of forming a resilient cutter blade, which comprises bending the blade to produce a convex surface, holding said blade in its bent shape, abrading one edge of said convex surface in a plane at an angle to the normal plane of said blade completely through said edge to remove metal of gradually increased amounts from spaced points on said edge to a point intermediate said spaced points and form a beveled and curved scallop between said spaced points, and repeating the operation at intervals throughout the length of said blade.

JOHN HANSEN.
